PORTABLE HEEL PRESS AND DRIER

Kenneth Afton Nutt, Delaware, Ohio

Application July 22, 1942, Serial No. 451,915

2 Claims. (Cl. 12—48)

The invention relates to a portable machine for holding, pressing and drying shoe heel blanks, the primary object of the invention being to provide a convenient and efficient machine for use in connection with heel building machines of various types, whereby a multiplicity of shoe heels, constructed by placing heel lifts one upon the other after application of cement, glue, and/or varnish thereto, may be simultaneously subjected to the pressure and air drying necessary to unite the lifts and completely dry the resultant heels, the machine being easily movable from one heel building machine to another.

Other important objects and advantages of the invention will be apparent from a reading of the following description taken in connection with the appended drawings, wherein for purposes of illustration a preferred embodiment of the invention is shown.

In the drawings:

Figure 1 is a general right hand side elevational view of the embodiment.

Figure 2 is a left hand end elevational view of Figure 1.

Figure 3 is a general transverse vertical sectional view taken through Figure 1 along the line 3—3 and looking toward the right in the direction of the arrow.

Figure 4 is an enlarged fragmentary transverse vertical sectional view taken through Figure 2 along the line 4—4 and looking in the direction of the arrow.

Figure 5 is an enlarged fragmentary longitudinal vertical sectional view taken through the right hand portion of Figure 1 to illustrate the automatic roll stop.

Referring in detail to the drawings, the numeral 5 generally designates a light weight frame consisting of a pair of upper longitudinal side members 6, an elongated base 7, rear vertical members 8 connected at their upper and lower ends to the members 6 and the base 7, the first front vertical members 9 and the second vertical members 10, which are connected at their upper and lower ends to the upper members 6 and the base 7, the side assemblies thus provided being spaced and connected by upper and intermediate cross members 11 and 12, respectively, and by upper and intermediate rear cross members 14 and 15, respectively, the latter being connected to intermediate portions of the rear vertical members 8.

A transverse axle 16 is supported in bearings 17 mounted on the upper longitudinal members 6 at a point slightly to the rear of the middle

thereof as illustrated in Figure 1 of the drawings, the said axle traversing and being fixed with respect to a hub 18 having flanges 19 between which are fastened flat relatively wide spokes 20 which are equally circumferentially spaced with respect to each other. The outer end portion of the rear side of each spoke 20 has fastened thereto a relatively wide flat plate 21 on whose radially inward edge is a right angular flange 22 which projects in a clockwise direction as seen in Figure 1 of the drawings.

Extending through each three adjacent cross members 21 adjacent the outer ends thereof are pairs of inner and outer arcuate rods or wires 23 and 24 which have heads 25 abutting the rear-most plate, with nuts 26 bearing against the outer side of the other extreme plate 21, whereby the said pairs of arcuate rods or wires are mounted in place.

20 Between each pair of adjacent spokes the portions of the rods or wires 23 and 24 subtended thereby have slidably mounted thereon the clamping plates 26 which are substantially the same in width and shape as the plain portion of the plates 21. Helical springs 27 and 28 are compressed between the plates 26 and the spoke remote from that spoke which carries the adjacent plate 21, the plate 26 being thereby yieldably urged toward the plate 21 so as to clamp the opposite ends of a plurality of shoe heels 29 which have been placed in relation to the plates 21, as illustrated in Figure 1 of the drawings, so that no portion of the clamping mechanism touches any portion of the surfaces of the heels 29 during the drying thereof except the tops and bottoms thereof. The plates 21 and 26, in conjunction with the wires or rods 23 and 24, and the springs 27 and 28, provide multiple spring pressed clamping drying racks for pluralities of heels, which are placed in side by side relation transversely with respect to the drying wheel which is generally designated 30.

The drying wheel 30 is normally to be manually rotated in a clockwise direction as seen in Figure 1 of the drawings, and to prevent reverse rotation of the wheel an automatic roll stop is mounted on the rear cross members 14 and 15, as shown in Figure 5 of the drawings. This roll stop comprises a stationary horizontal arm 31 which is formed with a hole to slidably receive the compressible rod 32, the rod having composed thereon an expanding helical spring 33 which expands against the upper generally horizontal arm 34 which is hinged as indicated by the numeral 35 to the upper cross member 14, with

the upper end of the rod 32 also pivoted to the arm 34. The arm 34 extends out beyond the arm 31 a sufficient distance to in its normal position be engaged by the outer end of any spoke 20 in the manner indicated in Figures 1 and 5 of the drawings, so that reverse rotation of the wheel 30 will be positively prevented. It will be noted that the capability of the arm 34 to subside against the tension of the spring 32 will permit the ends of the spokes 20 to pass the roll stop when the wheel 30 is rotating in the proper clockwise direction.

Another roll stop is provided on the second front vertical members 10, the same comprising a vertically elongated plate 36 secured at its upper and lower ends to the upper and intermediate cross members 11 and 12 at the front of the frame, the stop comprising a slotted arm 37 which is hingedly mounted as indicated by the numeral 38 in the space between the bottom of the cross member 11 and the plate 36, with the plate 37 mounted above the hinge element so as to abut the underside of the cross member 11 and be normally held in a rearwardly declining position as illustrated in Figure 4 of the drawings, in which its rearward end is in stopping relation to the outer end of any of the spokes 20. A rod 39 hinged as indicated by the numeral 40 below the hinge 38 traverses the slot in the arm 37 and has circumscribed thereon an expanding spring 41 which is compressed between the plate 36 and the arm 37 in the full line position shown in Figure 4 of the drawings. A cable 42 has its upper end connected as indicated by the numeral 43 to the outer end of the arm 37, the cable being trained over a pulley 44 on the plate 36 and under a pulley 45 on the lower portion of the right hand front vertical member 10 from which it rises to attachment to the lower side of the lever 46 which extends beyond the right hand side of the frame as shown in Figure 2 of the drawings and has its opposite end pivoted on a rod 47 mounted between the first and second front vertical members 9 and 10 on the left hand side of the frame 5. A helical spring 48 is stretched between the right hand extension of the lever 46 and an upper part of the vertical member 10 to keep the lever 46 normally in an inoperative or elevated position.

At a point intermediate the sides of the frame, a pivot pin 49 traversing an intermediate part of the lever 46 connects thereto the lower end of a vertical connecting rod 51 which has its upper end pivoted on a pin 52 to the inner end of normally upwardly and inwardly inclined levers 53 and 54 which are pivoted as indicated by the numerals 55 and 56 adjacent their laterally outward ends on pivot pins extending between the intermediate cross members 12.

The bifurcated extreme outer ends of the levers 54 and 53 have pivoted between the arms 57 thereof the lower ends of upwardly and inwardly inclining bars 58 and 59 which lie against the laterally outward edges of the plates 21 and 26 on the wheel 30, as illustrated in Figure 2 of the drawings. The bars 58 and 59 are precluded from any substantial lateral outward movement by the presence of beveled blocks 60, being limited only to such lateral outward movement as will enable the said plates to push the bars 58 and 59 aside to enable rotation of the wheel 30. As shown in Figure 2 of the drawings, the extreme upper ends of the bars 58 and 59 reach to the space between adjacent plates 21 and 26 so that when the lever 46 is released from a depressed

position and is moved upwardly to the full line position shown in Figure 2 of the drawings by the action of the spring 48, the upper ends of the bars 58 and 59 will engage the adjacent plate 26 and push the plate 26 away from the companion stationary plate 21 and thereby open the rack to enable removal of dried heels therefrom, and prepare the rack for reception of heels to be pressed and dried. It is to be observed that when the lever 46 is depressed the cable 42 is relaxed so as to permit the spring 41 to push the holding arm 37 into its elevated spoke engaging and wheel stopping position, whereas in the elevated position of the lever 46 the cable 42 is under tension so as to hold the arm 37 in a depressed non-stopping position, permitting free rotation of the wheel 30 as regards the arm 37.

A treadle 61 hinged intermediate the ends of a base 63 extending along the front of the base 7 of the frame 5 extends in a right hand direction and overlies a pin 64 projecting forwardly from the outer end portion of the lever 46. This treadle is provided for convenience in depressing the lever 46 by placing the foot of the operator upon the treadle and releasing the same upwardly in an obvious manner. It will be understood that when a new plurality of heels to be pressed and dried on the wheel has been placed upon the plate 21 then in position, permitting the treadle 61 to rise by removal of the operator's foot from the treadle, permits the plate 26 to move toward the plate 21 and clamp the heels in place.

Although there is shown and described herein a preferred embodiment of the invention, it is to be definitely understood that I do not desire to limit the application of the invention thereto except as may be required by the scope of the subjoined claims.

Having described the invention, what is claimed as new is:

1. A portable machine for holding, pressing and drying shoe heel blanks formed of superimposed lifts freshly cemented together and/or varnished, comprising a frame, a manually rotatable rotor horizontally journaled on said frame, said rotor comprising circumferentially arranged heel blank racks, each rack consisting of a stationary plate and a movable plate spring pressed toward the stationary plate for clamping a plurality of heel blanks with the plates engaging only the upper and lower ends of the heel blanks, positioning means for holding the rotor in a selected position of rotation, and treadle-operated means for operatively engaging the movable plate of the corresponding rack to move the movable plate in a direction away from the stationary plate to enable removal and replacement of one or more of the plurality of heel blanks from the rack, said rotor comprising a hub, spokes radiating from said hub, at least one circumferentially extending rod reaching between each adjacent pair of spokes, said stationary plate being secured to one of the spokes, and said movable plate being supported for movement on said rod, and expanding spring means compressed between the movable plate and the other adjacent spoke.

2. A portable machine for holding, pressing and drying shoe heel blanks formed of superimposed lifts freshly cemented together and/or varnished, said machine comprising a frame, a manually rotatable rotor horizontally journaled on said frame, said rotor comprising circumferentially arranged heel blank racks, each rack consisting of a stationary plate and a movable

plate spring pressed toward the stationary plate for clamping a plurality of heel blanks with the plates engaging only the upper and lower ends of the heel blanks, positioning means for holding the rotor in a selected position of rotation, and treadle-operated means for operatively engaging the movable plate of the corresponding rack to move the movable plate in a direction away from the stationary plate to enable removal and replacement of one or more of the plurality of heel blanks from the rack, said rotor comprising a hub, spokes, radiating from said hub, at least one circumferentially extending rod reaching between each adjacent pair of spokes, said stationary plate being secured to one of the 15

spokes, and said movable plate being supported for movement on said rod, and expanding spring means compressed between the movable plate and the other adjacent spoke, said treadle-operated means including reach bars supported on said frame for vertical movement to engage one of the movable plates to push the same away from its companion stationary plate when the reach bars are elevated from said positions, a treadle adapted to be depressed to elevate the reach bars, and operating connection means operatively connecting said treadle with said reach bars.

KENNETH AFTON NUTT.
